ATTORNEY

UNITED STATES PATENT OFFICE.

DE WATT PEPPER, OF NEW MILFORD, CONNECTICUT.

ADJUSTABLE CHAIR.

1,212,808.

Specification of Letters Patent. Patented Jan. 16, 1917.

Application filed May 31, 1916. Serial No. 100,906.

To all whom it may concern:

Be it known that I, DE WATT PEPPER, a citizen of the United States, residing at the town of New Milford, county of Litchfield, State of Connecticut, have invented certain new and useful Improvements in Adjustable Chairs; and I do declare the following to be a full, clear, and exact description of the invention, such as will enable others skilled in the art to which it appertains to make and use the same.

My invention relates to adjustable chairs, but more particularly has reference to a chair of this description especially adapted and constructed for the purpose of utilizing what is known as a "bustle back."

In Letters Patent No. 1,125,167, issued to me Jan. 19, 1915, I showed and described an adjustable chair equipped with the usual upholstery, and in which the lower edge of the chair back always swung above the rear edge of the chair seat, but I found that the construction of this chair was not at all adapted for the use of a bustle back, because the upholstery would become crushed and worn by reason of the fact that the lower portion of the back always swung above the rear portion of the seat.

The object of the present improvement is to provide a chair whose adjustments may be made not only without crushing, or, in fact, contacting adjacent upholstered portions, but also without leaving any gap between the back and seat such as would permit of the insertion or pinching of the clothing of the occupant of the chair.

Further objects of my invention will appear from the description hereinafter given, and from the accompanying drawings which illustrate a preferred embodiment of my invention and in which—

Figure 1 is a side elevation partly in section of my improved chair with the parts in their normal position with the chair back in its comparatively vertical adjustment. Fig. 2 is a similar view showing the position that the parts assume when the chair back is lowered so as to adapt the chair for the reclining of the occupant, and Fig. 3 is a front elevation of the chair.

Similar numerals of reference denote like parts in the several figures of the drawing.

1 is the stationary frame of the chair and 2 the seat having in its forward lower edge 55 a jog 3 which rests loosely on a cross bar 4 of the chair frame, so that said seat is capa-

ble of free rocking movements, of a pivotal nature, upon said cross bar. 5 is the upholstery of the seat 2.

6 is the back of the chair having secured thereto at opposite sides bracket fixtures 7, and 8 are similar bracket fixtures secured to the opposite sides of the back of the frame 1, and through these fixtures extends a rod 9, whereby the back 6 is pivotally secured to the chair frame.

10 is a downward extension of the back which extension is considerably below the level of the seat, and 11 are links whose extremities are pivoted respectively to the ends of the extension 10 and to the opposite side walls of the seat frame. It will, of course, be understood that these links connect the back with the seat at opposite sides, although I have only shown one of these links in the drawings.

12 is a coil spring whose extremities are connected respectively with the back of the frame and with the lower part of the seat, the function of this spring being to assist in returning the parts to normal position, and while this spring is not a feature that is essential to my invention, I prefer to use it.

13 is the upholstery at the upper part of the back and 14 is the upholstery at the lower portion of the back which protrudes very much after the fashion of a bustle, and chairs having this sort of upholstery are, therefore, known as "bustle back" chairs.

This upholstery 14 gradually decreases in thickness and is the thinnest at or about the point where the rear edge of the chair seat upholstery meets the lower edge of the bustle portion 14, and when the back of the chair is swung rearwardly the rear edge of the seat will be swung upwardly while at the same time the lower portion of the back will be swung both upwardly and rearwardly, the upward swing of this portion of the back enabling the swinging movements of the seat and back to be effected without any gap therebetween while the rearward swinging movement of the back constantly removes the bustle upholstery 14 from contact with the upholstery of the seat, so that the advantages of a bustle back are obtained and the adjustments made without the formation of any gap between the rear edge of the seat and the back and also without any crushing or friction between the upholstery.

Secured to the underside of the seat frame

are cross bars 15 which project laterally from said frame and abut against cleats 16 that are secured to the frame of the chair when said seat has reached a horizontal 5 position, these cleats being secured to the inside of the chair frame at opposite sides.

Any suitable means may be employed for locking the seat and back in their adjusted positions, a very simple embodiment of 10 which consists of a bracket 17 having an elongated slot 18, which bracket is secured to the side of the seat, a short bolt 19 with a head 20 being so located with respect to this bracket that the bolt extends through 15 the slot 18 while the head is in the immediate rear of the bracket, the bolt furthermore extending through an opening in the side of the frame 1 and terminating in a threaded portion, so that by driving a thumb 20 nut 21 on this threaded portion and against the face of any suitable striker plate 22 secured to the side of the frame 1, the parts may be drawn together so as to lock the 25 seat and consequently the chair back in any suitable adjusted position. Whenever the back is in its normal or upright position the lower outer edge of the extension 10 will abut against a cross piece 23 which forms a 30 part of the chair frame and thereby prevent any further inward swing of the chair back.

For the further comfort of the user of the chair I have provided an adjustable foot rest, which consists of the usual footboard 24 that is hinged at 29 to the end of a platform 25 the rear portion of which latter extends within the frame of the seat and rests upon a cross piece 26 forming a part 35 of said seat frame, any suitable pin 27 extending through this platform 25 in the immediate rear of the cross piece 26 to prevent the withdrawal of the platform. The platform extends through an elongated opening 28 in the front part of the frame 1 so as to be capable of vertical movements 40 within certain limits.

A leg support 30 is pivotally connected to the part 24 by means of a link 31, one of these links being at each side of said support and when in use this leg support at 45 its free end rests upon the seat as shown at Fig. 2.

By swinging the leg support 30 forward the parts will assume the position shown in dotted lines so that the underside of the 50 leg support may serve as a support for the soles of the feet, and in this connection it will be noted that one face of the support 55 can serve as a support for the feet while the other face can serve as a support for the 60 legs of the occupant of the chair, thus pre-

venting any dirt from the soles of the shoes soiling the legs of the trousers.

From the foregoing it will be readily understood that the pivotal point of the back of the chair is below the horizontal 65 level of the chair seat, and since the extension 10 of the chair back is below this seat and is connected thereto by means of the link 11, it will be readily understood that the operation of my new improved 70 chair in its adjustments can be effected without leaving any gap between the seat and the back and without injury to the upholstery in the slightest degree. Also, when the foot rest is not desired the part 24 may 75 be swung to horizontal position and the part 30 allowed to lie flat against the platform 25, whereupon the entire foot rest structure may be pushed within the chair frame so that no part of the same except the 80 rest 24 can be seen, this rest then appearing flat up against the seat frame as shown at Fig. 1.

Having thus described my invention what I claim as new and desire to secure by Letters Patent is:—

1. In a chair, the combination of a stationary frame, a seat pivotally connected at its front edge to the front of said frame and capable of swinging movements from 90 said pivotal point, integral cross bars carried by said seat and having their ends extending beyond the respective seat sides, and integral cleats common to the cross bars secured to the stationary frame and against 95 which said cross bars abut when the seat is swung to horizontal position.

2. In a chair, a frame, a seat pivoted at its front to the frame, a back pivoted to the frame, links pivoted to the back and 100 seat, a bar pivoted at one end to the seat and having its other end slotted, a bolt connected to the frame and extending through the slot of said bar and having a head engaging the bar, and a nut on the bolt for 105 engaging the frame whereby to bind the bar against the frame.

3. In a chair, a frame, a seat pivoted at its front to the frame, a back pivoted to the frame, links pivoted to the back and 110 seat, a bar pivoted at one end to the seat, and means to clamp the bar against the frame to lock same.

In testimony whereof I affix my signature in presence of witnesses.

DE WATT PEPPER.
